UNITED STATES PATENT OFFICE.

HALCYON SKINNER, OF YONKERS, NEW YORK.

TUFTED WOVEN FABRIC.

SPECIFICATION forming part of Letters Patent No. 543,659, dated July 30, 1895.

Application filed December 17, 1894. Serial No. 532,029. (No model.)

To all whom it may concern:

Be it known that I, HALCYON SKINNER, of Yonkers, in the county of Westchester and State of New York, have invented a new and useful Improvement in Tufted Woven Fabrics, of which the following is a specification.

This invention relates to tufted woven fabrics in which, as in what are known as "Moquette" carpets, the tufts are looped around some of the weft-threads and bound thereto by some of the warp-threads.

In a fabric embodying my said invention the rows of tufts follow each other in series of four and the weft-threads follow each other in series of eight, four alternating ones of the said weft-threads passing through the loops of the tufts and being so interwoven with the warp-threads as to retain the tufts, and the intervening ones of the said weft-threads being so interwoven with the warp-threads as to form a back or body filling. I will proceed to describe this fabric with reference to the accompanying drawings, and afterward to point out its novelty in claims.

Figure I represents a section of the fabric parallel with the warp. Fig. II is a diagrammatic plan view showing the position of the warp-threads when the shots of tuft-weft are put in. Fig. III is a corresponding plan view showing the position of the warp-threads when the shots of back or body weft are put in.

Similar letters of reference designate corresponding parts in all the figures.

In carrying out my invention the warp is divided into sets of four and distributed in four leaves of heddles, and eight movements of the harness and eight shots of filling are required for each series of four successive rows of tufts. The four warps of each set are designated in the drawings a' a^2 a^3 a^4 , respectively. The four alternating weft-threads of the series which pass through and secure the loops of the tufts, and which are woven into the face of the fabric, are designated, respectively, 1^* 2^* 3^* 4^* , and the intervening weft-threads, which are woven into the back of the fabric, are designated, respectively, 1^2 3^4 . The tufts are designated b' b^2 b^3 b^4 .

The operation of the weaving is as follows: The first shedding of the harness raises one warp-thread—for instance, a' —of each set of four and depresses all the others, and a shot

1^* of the tuft-weft is inserted. The second shedding raises all the warp-threads except a^2 , which it depresses, and a shot 1 of the back weft is inserted. The third shedding raises the warp-thread a^3 and depresses all the others, and the second shot 2^* of tuft-weft is inserted. The fourth shedding raises all the warp-threads except a^4 , which it depresses, and the second shot 2 of back weft is inserted. The fifth shedding raises the warp-thread a^2 and depresses all the others, and the third shot 3^* of tuft-weft is inserted. The sixth shedding raises all of the warp-threads except a' , which is depressed, and the third shot 3 of back weft is inserted. The seventh shedding raises the warp-thread a^4 and depresses all the others, and the fourth shot 4^* is inserted. The eighth shedding raises all the warp-threads except a^3 , which it depresses, and the fourth shot 4 of back weft is inserted. The tufts may be introduced between the warp-threads in any well-known or convenient manner, a row of tufts being inserted before each shot of tuft-weft.

It will be observed by reference to Fig. 1 that each tuft-weft thread and the second back-weft thread on each side of it are bound by the same warp-thread.

I have herein referred to tuft-weft and back or body weft, but these wefts may be all alike and are only separately designated for the sake of facilitating the explanation of the structure of the fabric. One shuttle only is necessary, and that may be operated in the same way as in plain weaving.

An important merit of the fabric having the warp and weft interwoven and the tufts bound as herein described, is that the warp-threads may be beaten up more closely together than in fabrics of this class heretofore manufactured, and that a more solid back is obtained, while the tufts are held very firmly in an upright position.

What I claim as my invention is—

1. A tufted woven fabric consisting of warp threads, weft threads and tufts looped around some of the weft threads and in which the rows of tufts follow each other in series of four, and the weft threads follow each other in series of eight, four alternating ones of the said weft threads being tuft-weft and the intervening ones being back weft and each tuft

weft thread and the second back weft thread on each side of it being bound by the same warp thread, substantially as herein set forth.

2. A tufted woven fabric consisting of warp 5 threads, weft threads and tufts looped around some of the weft threads and in which the rows of tufts follow each other in series of four, the weft threads follow each other in series of 10 eight and the warp threads are divided in sets of four, four alternating ones of the said

weft threads being tuft-weft and the intervening ones being back weft and each warp thread binding one of the back-weft threads and the second tuft weft thread on each side of it, substantially as herein described.

HALCYON SKINNER.
